UNITED STATES PATENT OFFICE

EDWIN S. PRIDHAM AND PETER L. JENSEN, OF OAKLAND, CALIFORNIA, ASSIGNORS TO
THE MAGNAVOX CO., OF OAKLAND, CALIFORNIA, A CORPORATION OF ARIZONA

SOUND-REPRODUCING DEVICE

Application filed June 14, 1922. Serial No. 568,309.

This invention relates to sound reproducing devices, and has for its object to combine in a single instrument a phonograph and an electrical sound reproducer with means for 5 optionally placing one or the other into communication with a horn whereby sound waves may be reproduced either electrically or acoustically.

The device includes an electrical sound amplifier which is so arranged that it may be 10 used in connection with the phonograph and at other times can be hooked up with a radio-receiving set to reproduce the sounds in greatly amplified tone.

One form which our invention may assume 15 is exemplified in the following description and illustrated in the accompanying drawings, in which—

Fig. 1 shows a diagram of an apparatus 20 embodying our invention.

Fig. 2 shows a front view of a phonograph cabinet within which the mechanism is arranged.

In its present form, the device comprises 25 a horn 10, which is preferably arranged within a cabinet 11. This horn has a branch conduit 12 extending to a swinging tone arm 13 which carries a phonograph reproducer 14. Another branch conduit 15 extends to an electro-dynamic telephone receiver 16. Preferably, this receiver is of the type shown and described in our prior application, Serial No. 377,354, being known commercially as a "Magna vox". Between the branch conduits 30 12 and 15 is a valve 17, pivoted at 18 and adapted to be moved to permit one branch to be put into communication with the horn, while shutting off the other branch. The electro-dynamic receiver is adapted to be 35 hooked up to a radio-receiving set, as shown at K in dotted lines in Fig. 2.

The phonograph reproducer 14 is shown as 40 co-operating with a sound record 19 carried on a turn-table 20 for ordinary phonographic playing. In addition to the reproducer 14 we show a combined phonograph reproducer 45 and transmitter 21 carried by a swinging support 22 and having electrical connections with the electro-dynamic receiver 16 such 50 that the sounds from the phonograph record

may be transmitted through the electro-dynamic receiver and sent out through the branch 15 in greatly amplified tone.

The electrical connections include a four-pole double-throw switch 23 arranged upon the cabinet 11. The switch blades are pivoted at points A, B, C and D and are adapted to co-operate when in one position with switch terminals E, F, G and H, and when in their other position with switch terminals I, J, K and L. Points A and B are connected by wires 24 and 25 with a movable coil 26 on the electro-dynamic receiver. This coil is fixed to the diaphragm 27 of the receiver. Points C and D are connected by wires 28 and 29 with an electro-magnet 30 of the said receiver. Terminals E and F are connected by wires 31 and 32 with the radio-receiving set K, and terminals G and H are connected by wires 33 and 34 with the battery of the radio-receiving set. When the switch is thrown to engage the terminals E, F, G and H the telephone currents from the radio-receiving set 55 pass through the electro-dynamic receiver where they are amplified and sent out 60 through the branch conduit 15 and horn 10.

Terminals K and L are connected by wires 35 and 36 with the combined reproducer and transmitter 21. In the last-named circuit we show a battery 37 and a rheostat 38. The other terminals I and J are connected by wires 39 and 40 with the wires 35 and 36 and include a condenser 41. When the switch is thrown to contact with the terminals I, J, K and L, the sounds from the combined reproducer and transmitter are transmitted telephonically to the electro-dynamic receiver 16 and sent out in amplified tone through the branch conduit 15 and horn 10.

In addition to the electrical reproduction 85 and amplification of the phonographic sounds, the phonograph may be played in the ordinary way through the reproducer 14 and branch conduit 12.

Preferably the entire mechanism above described is housed in a single cabinet which is also designed to contain the radio-receiving set and its batteries.

Various changes in the construction and arrangement of the several parts herein 90 100

shown and described may be employed without departing from the spirit of our invention as disclosed in the appended claims.

Having thus described our invention, what we claim and desire to secure by Letters Patent is:

1. In a sound reproducing device, the combination with a sound record, a combined phonographic reproducer and transmitter co-operating with the sound record, an electrically operated telephone receiver, a radio receiver set, electrical connections between the telephone receiver and the transmitter aforesaid, electrical connections between the telephone receiver and the radio-receiving set, and a switch for controlling said connections whereby to connect the receiver with the phonograph or with the radio-receiving set at the option of the operator.
2. In a sound reproducing device, the combination with a sound record, a phonographic reproducer co-operating therewith, a combined sound reproducer and transmitter also co-operating with said record, an electro-dynamic receiver, a horn having a branch conduit connected to the first-mentioned sound reproducer and a second branch conduit connected with the electro-dynamic receiver, means to place either branch conduit into communication with the horn while closing the other and electrical connections between the combined reproducer and transmitter and the electro-dynamic receiver whereby the sound waves from the phonograph may be transmitted through the electro-dynamic receiver for electrical reproduction or through the first-mentioned reproducer for acoustical reproduction.
3. In a sound reproducing device, the combination with a sound record, a phonographic reproducer co-operating therewith, a combined sound reproducer and transmitter also co-operating with said record, an electro-dynamic receiver, a horn having a branch conduit connected to the first-mentioned sound reproducer and a second branch conduit connected with the electro-dynamic receiver, means to place either branch conduit into communication with the horn while closing the other, electrical connections between the combined reproducer and transmitter and the electro-dynamic receiver whereby the sound waves from the phonograph may be transmitted through the electro-dynamic receiver for electrical reproduction or through the first-mentioned reproducer for acoustical reproduction, radio receiving set, and electrical connections between said electro-dynamic receiver and radio-receiving set and a switch to control such electrical connections whereby to connect said receiver either with the phonographic reproducer and transmitter or with the radio-receiving set at the option of the operator.
4. In a sound reproducing device, the com-

bination of a phonograph sound record, an electrical pick-up for converting the recording upon said sound record into electrical impulses, a radio receiving circuit, an electrically operated sound reproducer common to both said pick-up and said radio receiving circuit, and means for selectively connecting said electrically operated reproducer to said pick-up or to said radio receiving circuit, whereby sound record or broadcast music may be reproduced at will.

EDWIN S. PRIDHAM.
